UNITED STATES PATENT OFFICE.

HERMAN A. POPPENHUSEN, OF EVANSTON, AND JOSEPH HARRINGTON, OF RIVERSIDE,
ILLINOIS.

STEAM-BOILER FURNACE.

1,027,667.

Specification of Letters Patent. Patented May 28, 1912.

Application filed April 12, 1909, Serial No. 489,290.

To all whom it may concern:

Be it known that we, HERMAN A. POPPENHUSEN and JOSEPH HARRINGTON, citizens of the United States, and residents of Evanston and Riverside, respectively, in the county of Cook and State of Illinois, have invented certain new and useful Improvements in Steam-Boiler Furnaces; and we do hereby declare that the following is a full, clear, and exact description thereof, reference being had to the accompanying drawings, and to the letters of reference marked thereon, which form a part of this specification.

15 This invention relates to furnaces for steam boilers and other uses, and the invention relates more specifically to improvements in the deflecting partition, wall or arch located over the fire grate and arranged 20 to direct the fuel gases over the burning fuel in the combustion chamber in such a way as to promote the combustion of the fuel gases.

The improvements constituting our invention 25 are applicable to furnaces provided with automatic stoking devices or means by which the fuel is advanced through the combustion chamber as it burns; and the deflecting partition, wall or arch is located 30 above the fuel feeding or advancing grate in such manner that the burning gases are directed forwardly over the fire bed toward the fuel feeding end of the furnace in their passage from the combustion chamber to the 35 smoke stack.

Among the objects of the invention is to provide a deflecting partition, wall or arch of this character which may be made of relatively small depth or thickness so as to occupy but little space in the furnace, and thereby enable the height of the furnace 40 to be materially decreased.

A further object of the invention is to provide a deflecting partition, wall or arch 45 which is supported by tubular water cooled members, through which water to cool said members may be supplied either from a boiler above the furnace or from an external source.

50 A still further object of the invention is to simplify the construction of the deflecting partition, wall or arch, to reduce the cost thereof and to provide a simple arrangement of water cooled supporting members

or girders for supporting the arch structure.

Another object of the invention is to promote the circulation of water through the water cooled supporting members or girders, whereby they may be maintained suitably cool.

We have herein shown our invention as embodied in a furnace having a traveling chain grate by which a layer of fuel is fed from the feed end of the furnace rearwardly, 65 but it will be obvious that it may be applied to furnaces having other forms of grates arranged to advance the fuel through the furnace during combustion thereof.

As shown in the drawings:—Figure 1 is 70 a vertical, longitudinal section of a boiler furnace provided with a deflecting partition, wall or arch, embodying our invention, taken on line 1—1 of Fig. 2. Fig. 2 is a horizontal section taken on the indirect line 75 2—2 of Fig. 1. Fig. 3 is a transverse vertical section taken on line 3—3 of Fig. 2, looking rearwardly.

As shown in the drawings, 10 designates as a whole the front wall of the furnace; 80 11 the side walls thereof; 12 the fuel feeding hopper at the front wall; 13 the traveling or chain grate upon which the fuel is fed and by which it is advanced into and through the furnace, and 14 designates the 85 bridge wall of the furnace located at the rear of the grate. A vertically movable gate 15 controls the feed of the fuel from the hopper 12 to the traveling grate.

The boiler herein shown is of that type 90 comprising a plurality of water tubes 17 extending from front to rear of the furnace and connected at their ends with front and rear headers 18 and 19, respectively, which are adapted for connection with a water drum above, (not herein shown) the tubes 95 extending downwardly and rearwardly from the front header 18 to the rear header 19.

20 designates, as a whole, the deflecting partition, wall or arch of the furnace to which our invention relates. Said partition, wall or arch extends forwardly and upwardly from the bridge wall to a point near the front wall of the furnace, a space being 100 left between the forward edge of the deflecting partition, wall or arch and the front wall, which space constitutes the outlet open-

ing for the upward or outward passage of the products of combustion on their way to the smoke stack. The said deflecting partition, wall or arch may be employed with or without a coking breast or fire arch 22 which, when employed, is located just in front, and above the forward end of, the partition, wall or arch, and extends rearwardly from a fire brick wall 23 which constitutes part of the front wall of the furnace above the fuel feed opening thereof.

The deflecting partition, wall or arch to which our present invention relates and the means for supporting the same are constructed and arranged as follows: The deflecting partition, wall or arch consists of a plurality of tubular, metal supporting members 24, 24 arranged parallel with each other and transversely of the furnace, and fire brick members 26, 26 which extend between and are supported at their side margins on said supporting members. The supporting members are designed to be cooled by circulation of water or other cooling medium therethrough. They are supported at their ends on the side walls of the furnace and extend through one side wall thereof (the right hand wall as herein shown) for connection, outside of the furnace, with circulating tubes or pipes for supplying cooling water thereto. At the other or left hand side wall of the furnace the tubular members are connected in pairs with headers 25 embedded in said latter wall, said headers affording communication between two adjacent supporting members. The headers 25 consist of rectangular metal boxes set into the masonry wall of the furnace and are provided with openings into which the adjacent ends of the tubular supporting members are inserted and secured. The box-like headers, when thus arranged, constitute means for firmly supporting the adjacent ends of the tubular supporting members on the side wall. The supporting members may be inclosed by fire brick or tile coverings 27 to protect the same from the heat of the furnace and to avoid cooling of the heated gases by direct contact of the latter with the supporting members. The members 26, which span the spaces between and are supported on the tubular members 24, 24, may be either flat or curved and are formed at their side margins to engage with supporting surfaces on the supporting members, or on the fire brick coverings therefor, if such coverings be employed. As herein shown, the arch sections 26 are inclined or beveled at their side edges and fit correspondingly inclined or beveled seats 28 at the opposite upper sides of the insulating coverings. The arrangement described places the arch members and the supporting portions of the insulating coverings under compression throughout the deflecting partition, wall or

arch, a condition in which fire brick, by reason of their friable nature, are least liable to breakage or injury from heat.

In order to avoid transverse pockets or recesses at the under side or face of the deflecting partition, wall or arch, and to make said underside of the arch comparatively smooth, we provide the arch sections or members 26 with filling extensions 30, 30 which extend downwardly and practically fill the spaces between the supporting members. Said filling extensions are herein shown as made integral parts of the arch members. Preferably, when such filling extensions are employed, they will be made of slightly less width than the distance between adjoining supporting members or the insulating coverings thereof, thereby accommodating said parts to expansion without undue stress.

Referring now to the means herein shown for circulating the cooling water through the hollow girders 25 to maintain the same suitably cool the same are made as follows: 35 designates a tube which extends downwardly and forwardly from the rear or lower boiler header 19 toward the bridge wall and is arranged to supply water to the tubular supporting members. Said tube may be one of the boiler tubes that is deflected or turned out of its usual position for this purpose. Said tube is carried outwardly through the adjacent side wall 11 of the furnace, it having an outward bend 36 which extends through said wall. The portion 37 of said tube which is located outside of said wall is arranged parallel to the wall and is connected exterior to the furnace wall by upwardly extending branches 40, 40 with the adjacent ends of alternate tubular supporting members 24. The other alternate tubular members are connected at their ends adjacent to the supply or distributing tube by upwardly extending branches 42, 42 with a discharge or collecting tube 43 located exterior to the side wall of the furnace. The said discharge or collecting tube 43 is provided at its forward end with an inwardly turned portion 44 which extends through the side wall of the furnace and is connected at its inner end within the furnace, with the lower side of the front or uppermost boiler header 18. The inlet and outlet branches 40 and 42 are detachably connected with the outer ends of the tubular supporting members by elbows or like fittings 46 to enable said branches to be readily disconnected from said supporting members. The flow of the cooling water is from the lower or rear boiler header 19 through the tube 37, thence through the branches 40 to and through the alternate hollow supporting member 24 with which said branches are connected; and the water is returned through the connecting headers 25 and the

other alternate tubular supporting members to the branches 42 from whence it is discharged through the collecting tube 43 to the upper front boiler header. By this arrangement it will be seen that the cooling water from the supply tube 37 passes to and fro through adjacent tubular supporting members and thence directly through the return tube 43 to the front or upper boiler header. Thus the tubular supporting members are connected to the front and rear boiler headers through the medium of the supply and return tubes in parallel, which affords less resistance to the passage of the water through said supporting members than if said hollow girders were connected to the supply and return tubes in series. The speed of circulation of the cooling water through said tubular supporting members is thus promoted.

It will be observed that in the construction shown the water is circulated through the hollow girders under the boiler pressure. Said girders are maintained filled with water, the circulation therethrough is positive, the cooler water entering the supply tubes from the lower header thereof, and the heated water passing from the return or collecting pipe to the upper header at a higher level. The water to cool the supporting members may, if desired, be supplied from a source external to the boiler.

The arrangement whereby the supply and return tubes are connected with the tubular supporting members exterior to the furnace wall is an advantage, inasmuch as it permits a ready disconnection of the said members from the supply and return tubes, and permits ready removal of the supporting members when it becomes necessary to replace one or more of them. Moreover, the exposure of the ends of the tubular supporting members at the exterior of the furnace wall permits the cleaning of the tubular members of incrustations that may form therein, and this may be effected by disconnecting the tubular supporting members from the branch supply and return pipe and inserting a cleaning implement into said tubular members.

It will be observed that the construction described provides a deflecting partition, wall or arch of a minimum depth, while affording means for firmly supporting the same in position over the furnace grate. By decreasing the depth of said partition, wall or arch, as compared to prior practice, we are enabled to materially decrease the height of the furnace, which is a great advantage in point of construction and compactness. The construction described possesses im-

portant practical advantage over the massive deflecting arch structure heretofore employed in furnaces which bridge between and are supported on the side walls of the furnace, not only because of the saving of space in the furnace and the lessening of the height of the furnace, but also because the arch is not so liable to break down by its own weight, and while comparatively light its construction is such as to amply support it. Moreover, our improved arch is capable of being more readily and economically repaired than the prior massive arch structures. This is obvious from a consideration of the fact that the arch members are so supported on the girders or supporting members as to be readily removed and replaced without the necessity of disturbing the structure of the whole, or any part thereof except the arch members to be removed and replaced. Moreover, the construction makes it possible to remove one or more of the supporting members or girders to repair or replace the same without the necessity of disturbing more than one of the arch members, one at each side of the supporting members or girders to be removed and replaced.

We claim as our invention:—

In a furnace, the combination with a combustion chamber and a grate, of a deflecting partition in said chamber embracing a plurality of horizontal, tubular, metal, water-cooled supporting members, extending transversely between and supported by the side walls of the furnace, headers by which said supporting members are connected in pairs, said headers being embedded in one side wall of the furnace and the ends of said supporting members being extended through the other side wall of the furnace, supply and return pipes located exterior to the last named side wall of the furnace, said supply and return pipes being located respectively below and above the ends of the supporting members and being inclined in a direction from the lower rear part of the furnace to the upper forward part of the same, and connecting pipes extending from one supporting member of each pair downwardly to the supply pipe and from the other supporting member of each pair upwardly to the return pipe.

In testimony that we claim the foregoing as our invention we affix our signatures in the presence of two witnesses, this 29th day of March A. D. 1909.
